UNITED STATES PATENT OFFICE.

ELMER E. MILLER, OF MILLERSBURG, PENNSYLVANIA.

TRIGGER MECHANISM.

Application filed January 10, 1923. Serial No. 611,738.

To all whom it may concern:

Be it known that I, ELMER E. MILLER, a citizen of the United States, residing at Millersburg, in the county of Dauphin and

5 State of Pennsylvania, have invented certain new and useful Improvements in Trigger Mechanisms, of which the following is a specification, reference being had to the accompanying drawings.

10 This invention relates to single trigger firing mechanisms for double barrel guns of that type wherein the trigger mechanism may be set to fire either barrel by a pull upon the trigger, a second pull upon the 15 trigger acting to fire the other barrel.

An important object of the invention is to provide a novel and improved trip mechanism which may be set to cause firing of either barrel upon an initial actuation of the trigger and the firing of the second barrel upon a second actuation of the trigger, embodying a setting means which may be employed to set the trip to fire either barrel as may be selected upon such initial actuation, the setting means being such that when 25 in the neutral position movement of the trigger is positively prevented thereby.

A still further object of the invention is to provide a trip of this character including 30 such a setting means wherein the operation of the trigger to bring the trip into engagement with either of the sears of the hammer, brings into play means whereby the operation of either of the sears will cause release 35 of mechanism overcoming the action of the setting mechanism and automatically setting the trip in a position to engage the unreleased sear so that the second barrel may be fired.

40 Another object of the invention is to provide a device of this character which is extremely simple and which may be applied to practically all of those types of guns the sears of which are provided with lugs overhanging the trigger mechanism by means of which they may be tripped.

An additional object of the invention is to provide a simple and improved resetting mechanism whereby upon movement of the 50 safety latch to its extreme forward position, the positioning of the setting mechanism for the firing trip in the neutral position and the locking of the trigger is automatically assured.

55 These and other objects I attain by the construction and arrangement shown in the

accompanying drawings wherein for the purpose of illustration is shown a preferred embodiment of my invention and wherein like reference characters designate like parts 60 throughout.

In the drawings:—

Figure 1 is a side elevation showing a breech mechanism of a double barrel gun constructed in accordance with my invention, the stock being shown in section; 65

Figure 2 is a similar view of the opposite side of the gun;

Figure 3 is a section on the line 3—3 of Figure 2;

Figure 4 is a sectional view on the line 4—4 of Figure 2, the trip being shown in dotted lines in neutral position and in full lines in position to operate the right hand sear; 75

Figure 5 is a diagrammatic view showing in dotted lines the trip positioned to operate the right hand sear and in full lines the result of the operation of the right hand sear of the trip; 80

Figure 6 is a view showing in dotted lines the trip positioned to operate the left hand sear and in full lines the result of the operation when the right hand sear is likewise being operated; and 85

Figure 7 is a detached detail view fully illustrating the novel features of my invention.

Referring now more particularly to the drawings, the numeral 10 indicates a trigger plate of a breech mechanism, 11 a trigger mount upon the upper surface of the plate and 12 a trigger pivoted in the mount and operating through a slot formed in the plate. The numerals 13 and 14 designate sears extending rearwardly from the breech plate 15 and operating in the usual manner to hold the hammers 16 in the cocked position and to release the same when the sears have the rear ends thereof moved in the direction indicated by the arrow. When in cocked or firing position, the body portion 17 of the sears 13 and 14 substantially parallel the upper surface of the trigger plate 10 in slightly spaced relation thereto. Each sear 13 and 14 is provided at its rear end with a tripping lug 18 extending over the rear end of the trigger 12 in spaced relation thereto. 90 95 100 105

In accordance with my invention I form upon the trigger 12 beneath the tripping lugs 18 of the sears a pair of lugs 19 between which I pivot a trip 20. This trip is pro- 110

vided at each side thereof with an arm 21 extending outwardly from the trip toward the adjacent side of the trigger plate 10. These arms substantially parallel the trigger 5 plate when the trip is in central or vertical position. Secured to the trigger plate beneath each of the sears 13 and 14 and at a point spaced from the rear end of the sear is a spring 22, this spring from its point of 10 contact curving upwardly for engagement with the body 17 of its associated sear, as indicated at 23, and then slightly downwardly, the curvature of the rear end of the spring being such that when the sear is in 15 released position, the rear end of the spring is in spaced relation to the trigger plate 10 and applies its tension to the overlying arm 21 of the trip 20. When, however, the sears are in the cocked position, these springs have 20 the rear ends thereof flatly engaged against the trigger plate 10 and in spaced relation to the arms 21 of the trip 20 provided this trip be in the central or vertical position above referred to. Accordingly if the trip is shifted 25 to one side and the trigger employed to release one of the sears from the cocking position, this sear during its upward movement will release its associated spring 22 so that the rear end thereof will bring its tension 30 to bear upon the associated arm 21 of the trip. The opposite arm 21 of the trip not being affected by the tension of its associated spring 22 is free to move and the trip accordingly swings about its pivot so that the head 35 or engaging end thereof, indicated at 25, is positioned beneath the tripping lug 18 of the other of the sears to engage thereagainst and operate the same when the trigger is again actuated.

10 It will accordingly be obvious that if some setting mechanism be provided whereby the trip may be initially moved to a position beneath one or the other of the sears so that upon movement of the trigger the sear will 15 be released, means are provided for automatically shifting the trigger trip to the other of the sears provided this setting mechanism is of such nature that it may be overcome by the action of the spring 22 which is 20 thus released. Such a mechanism I have herein disclosed and is substantially identical with the corresponding mechanism described and claimed in my co-pending application Serial No. 556,724, filed April 26, 1922 for 25 trigger mechanisms and safety devices therefor. This mechanism embodies a plate or standard 26 vertically arranged upon the trigger plate 10 immediately rearwardly of the trigger opening thereof to which is 30 pivoted upon a horizontal pivot and to swing longitudinally of the plate 10 a setting member 27. This setting member embodies an arm 28 engaged in an opening in an operating member 29 actuated through medium of 35 the usual thumb piece 30 located interiorly

of the breech mechanism where it is convenient to access. This thumb piece as is usual, may be shifted to any one of three positions, a forward position where the right barrel is to be fired first, a central or neutral 70 position where the gun is held from firing and the trigger against movement, and a rearward position where the left hand barrel is initially fired and is maintained in these positions by a resilient end 31 formed 75 upon the operating mechanism 29 having a lug 32 coacting with positioning notches 33 formed in the upper breech plate of the breech mechanism. Accordingly by the actuation of the thumb piece 30 the member 27 80 may be rotated about its pivot and arranged in any one of three positions corresponding to the right, safety and left positions of the thumb piece. The member 27 further embodies a substantially horizontally and rearwardly extending arm 34. This arm has secured thereto one end of a light spring 35, the opposite end of which extends through and operates in an opening formed in the arm 21 at the corresponding side of the lug 20, the engagement of the spring in the opening being such as to permit sliding movement of the spring through the opening but to prevent any but a very limited vertical play therein. 90

This spring is so proportioned that when the member 27 is in that position corresponding to the safe position of the thumb piece 30, the trip 20 is held in the central or vertical position above referred to. The 100 spring 35 is further of such slight strength that it is readily overcome by the tension of a spring 22 when released by its sear. Since when the thumb piece 30 is in the neutral position the trip is vertical and the 105 arms 21 accordingly horizontal, it will follow that upon movement of the thumb piece either forwardly or to the rear from the safe position, the corresponding elevation or declination of the rear end of the arm 110 34 will cause a corresponding movement of the spring and the spring engaged arm 21. If the thumb piece be moved rearwardly the arm is elevated and accordingly the 115 spring engaged arm 21 is elevated. In the present instance I have illustrated the right hand arm 21 as being engaged by this spring and accordingly such rearward movement would cause the trip to be inclined toward the left and assume a position beneath the 120 tripping lug 18 of the left hand sear 13 with the result that if the trigger be pulled the left hand sear and hammer will be operated initially. If, however, the thumb piece 30 be moved forwardly the arm 34 125 will be moved downwardly and the trip member 20 accordingly positioned to actuate the sear 14 initially. As hereinbefore described, upon pulling of the trigger the release of the spring 22 compressed by the 130

engaged sear will cause the trip member to be shifted to a position where it will actuate the sear of the opposite barrel upon a second actuation of the trigger.

5 The actuating mechanism 27 further includes a third arm 36 extending downwardly therefrom and which when the thumb piece is in safe position is positioned immediately above a lug 37 carried by the 10 trigger 12 in close proximity thereto. Upon attempted actuation of the trigger with the setting mechanism in this position, this lug will engage the lower end of the arm 36 preventing movement of the trigger until the thumb piece is again moved. The 15 lug 37 likewise serves as a stop to limit the movement of the trigger into forward or set position and has its upper surface cam shaped so that if the trigger is not fully 20 depressed, the engagement of the arm therewith will force the lug downwardly until the trigger assumes the proper position, thus overcoming to a great extent a quick or jerky firing. As is well known to those 25 familiar with the art, small particles of dirt or the like or possibly shreds of material loosened from the gun butt will often get between two portions of the breech mechanism causing the trigger to assume a 30 position slightly rearwardly of that normally assumed when released. The operator of the gun in handling the same naturally assumes that the trigger is in the full forward or set position and accordingly 35 will prematurely fire the gun in squeezing the trigger. This feature is entirely eliminated by the construction hereinbefore set forth. While I have illustrated a breech mechanism as embodying a double firing 40 preventer 38 such as disclosed in the prior application hereinbefore referred to, the same is not herein claimed or described, since the construction thereof has been in no wise patentably altered.

45 The numeral 39 indicates as a whole a common form of mechanism for locking the barrels B in the proper position with relation to the breech plate 15 and embodies a substantially vertical shaft 40 rotatably 50 mounted in the breech plate 15 and having at its lower end a crank 41 which is engaged with a locking bar 42 directed through the breech plate 15 longitudinally of the gun. The shaft 39 is rotated through 55 medium of a thumb lever 43 and is normally held in one position by means of a spring pressed plunger 44, the spring of which abuts solidly against the upper plate of the breech mechanism through medium of 60 its housing 45. This shaft when in its normal position through the coaction of its crank 41 with the locking bar 42 projects the locking bar forwardly for engagement in a notch 46 formed in an integral ex- 65 tension 47 depending from the barrels B

and which notch 46 is aligned with the locking bar 42 when the barrels B are in the proper position for firing with relation to the breech plate 15. When the lever 43 is moved to the dotted position shown in Figure 2 against the action of the spring 70 pressed plunger 44, the bolt or locking bar 42 is retracted to the position shown in the dotted lines in this figure and the barrels released for oscillation to the reloading or 75 charge extracting position.

In accordance with my invention I form in the stock S of the gun a bore 48 extending longitudinally of the stock and having its axis directed toward the upwardly extending arm 28 of the setting mechanism and communicating with a recess 49 in which this arm operates. The bolt 42 when in retracted position extends into a recess 50 formed in the forward end of the stock S and into this recess the forward end of a pin 51 mounted in the bore 48 normally extends. The rear end of this pin abuts the arm 28 in a manner hereinafter more fully described and the pin is held against excessive movement by a notch 52 formed in the side thereof and which notch receives the sleeve 53 surrounding the forward stock pin 54 by means of which the stock is secured to the breech mechanism. 80 In addition to limiting the movement of the pin, the notched engagement of the pin with the sleeve prevents the pin from slipping from the stock when the stock is removed from the breech mechanism. 85

In the operation of the gun, when the thumb piece 30 is in the forward position, the engagement of the arm 28 with the pin 51 has caused the same to be moved forwardly to its fullest extent within its bore 48 and to project well into the recess 50 into which the retraction of the bolt causes the rear end of the bolt to be positioned. The projection of the pin 51 into the path 90 of movement of the bolt 42 is for a distance equal to the distance through which the arm 28 moves at its point of engagement by the pin 51 in moving from the forward position to the safety or neutral position. Accordingly, if the lever 43 is actuated to "break" 95 the gun, the pin 41 is engaged by the bolt 42 and moved rearwardly and by its rearward movement, if the setting mechanism be in the forward position, moves the setting mechanism to such neutral position, placing 100 the gun in safety and preventing accidental firing thereof. It is well known to those familiar with the art that positioning at the intermediate of safety position is difficult, the lug 32 in entering the notches 33 in order 105 to move the same must have sufficient power applied thereto to depress the same against the action of the spring end 31 and this power is ordinarily sufficient to cause an entire shifting 110 movement of the safety mechanism from 115 its housing 45. This shaft when in its normal position through the coaction of its crank 41 with the locking bar 42 projects the locking bar forwardly for engagement in a notch 46 formed in an integral ex- 120 tension 47 depending from the barrels B

- one extreme position to the other. The operator must accordingly be very careful in handling the gun since he is liable, instead of positioning it to safety position, to swing 5 from one firing position to another with the result that the gun is ready for firing immediately upon relocking of the breech mechanism and is often accidentally discharged. It will be seen that by the mechanism 10 described no care is necessary to position the setting mechanism at the proper point. The operator after firing the gun may without looking at the same engage the thumb piece with his finger and force the same forwardly. If the setting mechanism is by this forward movement merely placed 15 in the safety position, no action of the setting mechanism results from the breaking of the gun. If, however, the movement is excessive and the setting mechanism is in 20 extreme or forward position, the pin in its rearward movement automatically places the same in the safety or neutral position and assures against accidental firing.
- 25 If the setting mechanism be left in the rearmost position or what in the present instance corresponds to the firing position of the left hand barrel until the gun be broken, attention is called to the fact that the pin 30 51 will then serve as a stop and that while the gun is broken and the bolt withdrawn, the trip may be shifted to position the setting mechanism and will be limited by the pin 51 to the neutral position. Thus, the 35 pin 51 serves with the trip in one position as an automatic setting device for the neutral position and when the trip is in the opposite position as a gauge to limit the movement of the setting mechanism.
- 40 I claim:—
1. In a single trigger mechanism for double barrel guns, a pair of sears, a trigger arranged between the sears, a sear trip pivoted upon the trigger for oscillation in a 45 vertical plane extending transversely of said sears, an arm extending outwardly from each side of said trip, springs for engagement with said arms, said springs being engaged and withdrawn from engagement with 50 the arms upon movement of the sears to cocked position, and means for shifting said trip upon the trigger to position the same for initial engagement with either of said sears, said means for shifting the trip embodying a part yielding to permit shifting of 55 the trip under the influence of either of said springs when released by its sear.
  2. In a single trigger mechanism for double barrel guns, a pair of sears, a trigger 60 arranged between the sears, a sear trip pivoted upon the trigger and shiftable thereon to engage either of said sears to move the same to operated position, a shifting mechanism for said trip whereby the trip may be 65 positioned to engage a selected sear, and 70 springs coacting with said trip and sears acting initially upon operation of a sear to assist the sear in its movement to operated position and then coacting with said trip to shift the trip upon the trigger to a position 75 for engagement with the other of the sears.
  3. In a single trigger mechanism for double barrel guns, a pair of sears, a trigger arranged between the sears, a sear trip pivoted upon the trigger and shiftable thereon to engage either of said sears to move the same to operated position, a shifting mechanism for said trip whereby the trip may be positioned to engage a selected sear, and springs 80 co-acting with said trip and sears acting initially upon operation of a sear to assist the sear in its movement to operated position and then coacting with said trip to shift the trip upon the trigger to a position for engagement with the other of the sears, said shifting mechanism embodying a part yielding under the influence of the spring released by a sear to permit shifting of the trip. 85
  4. In a single trigger mechanism for double barrel guns, a pair of sears, a trigger arranged between the sears, a sear trip pivoted upon the trigger and shiftable thereon to engage either of said sears to move the same to operated position, a shifting mechanism for said trip whereby the trip may be positioned to engage a selected sear, and springs 90 coacting with said trip and sears acting initially upon operation of a sear to assist the sear in its movement to operated position and then coacting with said trip to shift the trip upon the trigger to a position for engagement with the other of the sears, said shifting mechanism embodying a part yielding under the influence of the spring released by a sear to permit shifting of the trip. 95
  5. In a single trigger mechanism for double barrel guns, a pair of sears, a trigger arranged between the sears, a spring arranged beneath each sear and compressed thereby during its movement to cocked position, a trip pivoted upon the trigger for oscillation to positions engaging either of said sears, an arm extending outwardly from each side of the trip, the ends of said arms being arranged over the ends of the springs and being engaged by the springs when released by the sears, and means for shifting said trip upon the trigger to position the same for initial engagement with either of the sears, embodying a part yielding to permit shifting of the trip under the influence of the spring released by an operated sear. 100
  6. In a single trigger mechanism for double barrel guns, a pair of sears, a trigger arranged between the sears, a spring arranged beneath each sear and compressed thereby 105

- during its movement to cocked position, a trip pivoted upon the trigger for oscillation to positions engaging either of said sears, an arm extending outwardly from 5 each side of the trip, the ends of said arms being arranged over the ends of the springs and being engaged by the springs when released by the sears, means for shifting said trip upon the trigger to position the same 10 for initial engagement with either of the sears, embodying a member mounted for rotation, and a spring secured at one end to said member at a point spaced from the pivot thereof and having its opposite end 15 engaged with one of the arms of said trip, the last named spring being of less strength than either of the first named springs.
7. In a single trigger mechanism for double barrel guns embodying the usual trigger 20 sears and trip carried by the trigger, setting mechanism for the trip for shifting said trip to a position where it engages either of the sears or to a position intermediate the sears, said setting mechanism including an arm 25 extending in proximity to the trigger, and a lug carried by the trigger above which the arm passes, said arm when the setting mechanism is in the intermediate position being aligned with said lug to prevent movement 30 of the trigger, the upper face of said lug having a cam face coacting with the lower end of said arm over which the arm rides to insure placement of the trigger in set position.
- 35 8. In single trigger mechanism for double barrel guns, a breech mechanism, barrels hinged thereto, a locking bolt for the barrels shiftable longitudinally of the gun to barrel locking or unlocking positions, a trigger, 40 a pair of sears, one for each barrel, sear tripping mechanism coacting with the trigger, a setting mechanism for the tripping mechanism for setting the same to coact with either of said sears, said setting mechanism coacting with the trigger when in one 45 position to lock the trigger against movement to firing position, a stock having a recess in which said setting mechanism operates and a second recess into which said bolt extends when in the barrel unlocking position, a bore formed in the stock connecting said recesses, and a pin mounted in said bore and of a length equal to the distance between the rear end of the bolt when in unlocking position and the engaged portion of the setting mechanism when in said trigger locking position.
- 50 9. In single trigger mechanism for double barrel guns, a breech mechanism, barrels hinged thereto, a locking bolt for the barrels shiftable longitudinally of the gun to barrel locking or unlocking positions, a trigger, a pair of sears, one for each barrel, sear tripping mechanism coacting with the trigger for 55 each side of the trip, the ends of said arms being arranged over the ends of the springs and being engaged by the springs when released by the sears, said setting mechanism coacting with the trigger, a setting mechanism for the tripping mechanism for setting the same to coact with either of said sears, said setting mechanism coacting with the trigger when in one position to lock the trigger against movement to firing position, a stock having a recess in which said setting mechanism operates and a second recess into which said bolt extends when in the barrel unlocking position, a bore formed in the stock connecting said recesses, and a pin mounted in said bore and of a length equal to the distance between the rear end of the bolt when in unlocking position and the engaged portion of the setting mechanism when in said trigger locking position.
- 60 10. In single trigger mechanism for double barrel guns, a breech mechanism, barrels hinged thereto, a locking bolt for the barrels shiftable longitudinally of the gun to barrel locking or unlocking positions, a trigger, a pair of sears, one for each barrel, sear tripping mechanism coacting with the trigger, a setting mechanism for the tripping mechanism for setting the same to coact with either of said sears, said setting mechanism coacting with the trigger when in one position to lock the trigger against movement to firing position, a stock having a recess in which said setting mechanism operates and a second recess into which said bolt extends when in the barrel unlocking position, a bore formed in the stock connecting said recesses, and a pin mounted in said bore and of a length equal to the distance between the rear end of the bolt when in unlocking position and the engaged portion of the setting mechanism when in said trigger locking position.
- 65 11. In a single trigger mechanism for double barrel guns, a pair of sears, a trigger, a sear trip operable by the trigger and shiftable to positions where it is engageable with either of said sears upon movement of the trigger or to a position intermediate said positions, and selective mechanism for shifting the trip to any of said positions for holding the same therein including a part engaging the trigger upon movement of the trip from either of the first named positions to the other of the first named positions or from either of the first named positions to the last named position to shift the trigger to the fully set position.
- 70 12. In a single trigger mechanism for double barrel guns, a pair of sears, a trigger, a sear trip operable by the trigger and shiftable to positions where it is engageable with either of said sears upon the

movement of the trigger, and selective mechanism for shifting the trip to either of said positions for holding the same therein including a part engaging the trigger 5 upon movement of the selective mechanism to shift the trip from either of said positions to the other of said positions to force the trigger into set position.

13. In a single trigger mechanism for 10 double barrel guns, a pair of sears, a trigger, a sear trip operable by the trigger and shiftable to positions where it is engageable with either of said sears upon movement of the trigger or to a position intermediate 15 said positions, selective mechanism for shifting the trip to any of said positions and for holding the same therein including a part engaging the trigger upon movement of the trip from either of the first 20 named positions to the other of the first named positions or from either of the first named positions to the last named position to shift the trigger to the fully set position, and means operated by the breaking 25 of the gun when the selective mechanism is positioned to hold the trip in one of the first named positions for positively shifting the selective mechanism to the last named position.

14. In a single trigger mechanism for 30 double barrel guns, a pair of sears, a trigger, a sear trip operable by the trigger and shiftable to positions where it is engageable with either of said sears upon movement of the trigger or to a position intermediate 35 said positions, selective mechanism for shifting the trip to any of said positions for holding the same therein including a part engaging the trigger upon movement of the trip from either of the first named positions to the other of the first named positions or from either of the first named positions to the last named position to shift the trigger to the fully set position, and means operated by the breaking 40 of the gun when the selective mechanism is positioned to hold the trip in one of the first named positions for positively shifting the selective mechanism to the last named position, the selective mechanism 45 when in the last named position positively locking the trigger against movement.

15. In a single trigger mechanism for 50 double barrel guns, a pair of sears, a trigger, a sear trip operable by the trigger and shiftable to positions where it is engageable with either of said sears upon movement of the trigger or to a position intermediate 55 said positions, selective mechanism for shifting the trip to any of said positions for holding the same therein including a part engaging the trigger upon movement of the trip from either of the first named positions to the other of the first named positions or from 60 either of the first named positions to the last

named position to shift the trigger to the fully set position, the selective mechanism when in the last named position positively locking the trigger against movement.

16. In a single trigger mechanism for 70 double barrel guns, a pair of sears, a trigger, a sear trip operable by the trigger and shiftable to positions where it is engageable with either of said sears upon movement of the trigger or to a position intermediate 75 said positions, and selective mechanism for shifting the trip to any of said positions including an arm, a cam carried by the trigger and with which the arm co-operates upon movement of the trip from either of the first 80 named positions to the other of the first named positions or from either of the first named positions to the last named position to shift the trigger to the fully set position.

17. In a single trigger mechanism for 85 double barrel guns, a pair of sears, a trigger, a sear trip operable by the trigger and shiftable to positions where it is engageable with either of said sears upon movement of the trigger or to a position intermediate 90 said positions, and selective mechanism for shifting the trip to any of said positions including an arm, a cam carried by the trigger and with which the arm co-operates upon movement of the trip from either of the first 95 named positions to the other of the first named positions or from either of the first named positions to the last named position to shift the trigger to the fully set position, said arm when in the last named position 100 being positioned directly above said cam and positively locking the trigger against movement.

18. In a single trigger mechanism for 105 double barrel guns, a pair of sears, a trigger, a sear trip operated by the trigger and shiftable to engage and operate a selected sear upon initial operation of the trigger, and means released by an operated sear engaging the trip and shifting the same to a position 110 for engagement with the other sear, said means acting to assist the sear in its movement to operated position.

19. In a single trigger mechanism for 115 double barrel guns, a pair of sears, a trigger, a sear trip operated by the trigger and shiftable to engage and operate a selected sear upon initial operation of the trigger, and a spring released by an operated sear engaging the trip and shifting the same to a position 120 for engagement with the other sear, said spring acting to assist the sear in its movement to operated position.

20. In a single trigger mechanism for 125 double barrel guns, a pair of sears, a trigger, a sear trip operated by the trigger and shiftable to engage and operate a selected sear upon initial operation of the trigger, and means for shifting the trip into position for 130 engagement with either of the sears includ-

ing a part coacting with the trigger during shifting of the trip from a position to engage one sear to a position for engagement with the other sear to force the trigger into 5 fully set position.

21. In a single trigger mechanism for double barrel guns, a pair of sears, a trigger, a sear trip operated by the trigger and shiftable to engage and operate a selected sear 10 upon initial operation of the trigger, and means for shifting the trip into position for engagement with either of the sears including a part coacting with the trigger during shifting of the trip from a position to engage 15 one sear to a position for engagement with the other sear to force the trigger into fully set position, said part at a point intermediate said positions overlying the portion of the trigger with which it coacts to prevent movement thereof, and means operated by breaking of the gun for shifting said part to said 20 position when the part is positioned for initial operation of one of the sears and the gun is broken.

22. In a single trigger mechanism for

double barrel guns, a pair of sears, a trigger, a sear trip operated by the trigger and shiftable to engage and operate a selected sear upon initial operation of the trigger, means 25 for shifting the trip into position for engagement with either of the sears including a part coacting with the trigger during shifting of the trip from a position to engage one sear to a position for engagement with the other sear to force the trigger into fully set position, said part at a point intermediate said positions overlying the portion of the trigger with which it coacts to prevent movement thereof, and means operated by breaking of the gun for shifting said part to said 30 position when the part is positioned for initial operation of one of the sears and the gun is broken.

In testimony whereof I hereunto affix my 40 signature.

ELMER E. MILLER.
